UNITED STATES PATENT OFFICE.

HENDRICUS JOHANNES JACOBUS JABURG, JR., OF AMSTERDAM, NETHERLANDS.

ELECTRIC-ARC LAMP.

No. 861,856.

Specification of Letters Patent.

Patented July 30, 1907.

Application filed December 31, 1906. Serial No. 350,143.

To all whom it may concern:

Be it known that I, HENDRICUS JOHANNES JACOBUS JABURG, Jr., a subject of the Queen of the Netherlands, residing at Keizersgracht No. 541, Amsterdam, King 5 dom of the Netherlands, have invented certain new and useful Improvements in Electric-Arc Lamps, of which the following is a specification.

My invention relates to improvements in electric arc lamps and particularly to that type of lamp in which 10 the electrodes are disposed at a relative inclination to each other and which furthermore are adapted to be used in connection with either continuous or alternating currents.

One of the objects of this invention is the provision 15 of means for positively and automatically regulating the feed of the electrode.

Another object of the invention is to prevent any sudden shocking or jarring of the electrodes.

Still another object contemplated by this invention 20 is to insure frictional engagement of the terminals of the electrodes, thus preventing ashes adhering to the same.

To the accomplishment of the recited objects and others subordinate thereto, the preferred embodiment 25 of the invention resides in that construction and arrangement of parts hereinafter described, illustrated in the accompanying drawings, and embraced within the scope of the appended claims.

The drawing represents a longitudinal section 30 through an apparatus embodying my invention.

The numeral 1 designates the well known top plate upon which the guide rod 2 and regulating mechanism which is to be hereinafter described are arranged. The arc light electrodes 3 and 4 are respectively mounted upon holders 5—5 which are adapted to slide vertically 35 on the guide rod 2. To the top plate 1 are moreover connected two bearing rods 6, to the terminals of which is secured a supporting plate 7 which is provided with the usual ring 8 for holding the glass cylinder or economizer 9. The lower end of the left hand guide rod is 40 fixed on a contact plate 15 which is arranged on the supporting plate 7, the right hand guide rod, two of which being illustrated are adapted to be directly connected to the supporting plate 7. This last mentioned connection has been eliminated from the drawing in order 45 that the electrode, the regulating devices and their co-relative parts may be observed more clearly in said drawings. The electrode 3 projects through an opening, as at 10, and the electrode 4 extends through an elongated opening as at 11, both of said openings for the 50 respective electrodes being in the plate 7. The lower end of the electrode 3 rests, as usual, upon a supporting surface 12 which is made of any suitable refractory material and connected to the plate 7.

The carbon holder 5 of the electrode 3 is provided 55 with a laterally extending bar 13 and the carbon holder of the electrode 4 is suspended on said bar by means of

an eye. It will be noted that the eye is of considerable larger diameter than the diameter of the laterally extending bar 13, the function of which will be hereinafter described.

60

It is evident from the foregoing description that the lateral bar 13 will descend with the electrode 3 and owing to its connection with the holder 5 of the electrode 4 will cause the latter to also descend so that both of said electrodes will be uniformly and gradually consumed. On the under side of plate 1 is arranged a solenoid or electro magnet 14, the core 16 of which is hollow and contains a spiral spring 17, having one end connected with the top thereof in any suitable manner and having its other end connected to the rod 18 which is 65 guided in brackets 19 and 20 connected to a foot plate 21, the latter in its normal position resting on the supporting plate 7. When the core 16 of the solenoid 14 is made to assume its lowest position, as shown in the drawing, this foot plate 21 completely covers the elongated aperture 11 of the supporting plate 7 and in this position has moved the carbon 4 to the right, that is to say away from the supported carbon 3, this being the normal position when the lamp burns.

To one side of the electro magnet 14 is arranged a 70 magnetic cut out 22, the core 23 of which is provided with a contact stud 24 and a strap 25, the latter having a contact 26. On the top of the plate 1 are located two terminals 27 and 28 and at any desirable place within or without the lamp is arranged a supplementary resistance 29. The wire connections between the various parts of the lamps are arranged as follows:—The left hand guide rod 2 is connected to the terminal 27 and its contact plate to one end of the supplementary resistance, the upper end of which is connected to the 75 electro magnet 14. From the terminal 28 a rod 30 is arranged downward and connected by a wire with a magnetic cut out and by means of another wire to the contact stud 24 of the core 23 of the magnetic cut out 22. A rod 31 is connected to the bottom of the top 80 plate 1 and the upper end of said rod is connected to the winding coil of the magnetic cut out and the lower end is connected by means of a hanging wire with a carbon holder 5 of the movable carbon 4.

When the lamp burns, the electrodes and all other 85 parts of the lamp assume the positions shown in the drawing. If the circuit is cut out, the carbons remain in this position, but the core 23 of the magnetic cut out will then descend so that the contact stud 24 comes to rest on the contact 26. To make the lamp burn, the 90 current is taken in through terminal 27 by the rod 2, contact plate 15 and supplementary resistance 29, the electro magnet 14, the contact 26, the contact stud 24 and the rod 30, to the terminal 28. When the electro magnet 14 is energized the core 23 of the same will 95 raise the rod 18 with its foot plate 21 and by so doing will cause the electrode 4 to move towards the sup-

ported electrode 3 and thus induce the formation of an arc. The current will then pass directly to the movable electrode 4 and from the holder 5 of the same over the rod 31 to the winding coil of the magnetic cut out, 5 and over this coil by the rod 30 to the terminal 27. In passing through the winding coil of the magnetic cut out, the current will attract the core 23 of the same, whereby the contact 24—26 is interrupted, with the result that the electro-magnet 14 as well as the supplementary resistance are deenergized. The core 16 of the electro magnet is then no longer attracted and will consequently gravitate so that the foot plate 21 closes the aperture 11 and by so doing shuts off the interior of the lamp from the burning ends of the electrode. It 10 will thus be seen that the movement of the core 16 which takes place at the beginning of the burning of the lamp causes the movable electrode to move towards and from the supported one and as the movable one has a slight movement in the direction of the length of the carbon 4 and independent of the rod 13 and carbon 3 owing to the fact that the eye carried by the support 5 is considerably larger than the diameter of the bar 13 as hereinbefore recited, the points of the carbons are rubbed against each other. This initial 15 frictional engagement of the lower terminals of the electrodes wipes the ashes off and obtains a perfect contact of the electrodes. It is also obvious when using an alternating current, owing particularly to the fact that the electro magnet 14 is deenergized when 20 the arc lamp is burning that humming or jarring of the lamp is prevented.

What I claim is:

1. An electric arc lamp comprising a supported electrode and a movable electrode, a holder for the supported electrode, a bar rigidly connected to and extending from said holder, a holder for said movable electrode, said last mentioned holder having an eye loosely mounted on the bar of the holder, and guide rods for each of the holders. 35
2. An electric arc lamp comprising a supported electrode and a movable electrode, a holder for the supported electrode, a bar rigidly connected to and extending from said holder, a holder for said movable electrode, and means connecting said bar and holder for permitting a lateral and longitudinal movement of the movable electrode. 40
3. An electric arc lamp comprising a stationary supporting plate having a pair of openings, one of said openings being elongated, a supported electrode extending through the smaller of said openings, an apertured foot-plate mounted upon the supporting plate for closing the elongated opening therein, a movable electrode extending through said foot-plate and elongated opening, a holder for the supported electrode, a bar rigidly connected to and extending from said holder, a holder for said movable electrode, and guide rods for each of the holders. 45

trode, said last mentioned holder having an eye loosely mounted on the bar of the holder, a rod connected to 55 said foot plate and extending in substantially the same direction as the movable electrode and provided with means for moving it in such direction, and guide rods for each of the holders.

4. An electric arc lamp comprising a stationary supporting plate having a pair of openings, one of said openings being elongated, a supported electrode extending through the smaller of said openings, an apertured foot-plate mounted upon the supporting plate for closing the elongated opening therein, a movable electrode extending 60 through said foot-plate and elongated opening, a holder for the supported electrode, a bar rigidly connected to and extending from said holder, a holder for said movable electrode, the latter having an eye loosely mounted on the bar of the other holder to permit of a lateral and longitudinal 65 movement of the movable electrode, and a rod connected to said foot plate and extending in substantially the same direction as the movable electrode and provided with means for moving it in such direction.

5. An electric arc lamp comprising a stationary supporting plate having a pair of openings, one of said openings being elongated, a supported electrode extending through the smaller of said openings and closely fitting the same, an apertured foot-plate mounted upon the supporting plate closing the elongated opening therein, a rod having one terminal secured to said foot-plate and extending in substantially the same direction as the movable electrode, an electro-magnet for moving the rod in such direction, a hollow core therefor, a spring within said core and connected to the other terminal of said rod, a movable electrode extending through said foot-plate and elongated opening, and holders for the electrodes, and guide rods for each of said holders. 70

6. An electric arc lamp comprising a stationary supporting plate having a pair of openings, one of said openings being elongated, a supported electrode extending through the smaller of said openings and closely fitting the same, an apertured foot-plate mounted upon the supporting plate for closing the elongated opening therein, a movable electrode extending through said foot-plate and elongated 75 opening, means for causing an initial frictional engagement of the terminals of said electrodes, said means comprising a rod having one terminal secured to said foot-plate and extending in substantially the same direction as the movable electrode, an electro-magnet for moving the rod in such direction, a hollow core therefor, a spring within said core and connected to the other terminal of said rod, a bar rigidly connected to and extending from the holder of said supported electrode, the holder of said movable electrode having an eye loosely mounted on the 80 bar of the other holder, and guide-rods for each of said holders. 85

In testimony whereof I have hereunto set my hand in presence of two subscribing witnesses.
